UNITED STATES PATENT OFFICE.

JOSIAH C. GOODING, OF ST. LOUIS, MISSOURI.

DESIGN FOR A DESK AND SEAT.

SPECIFICATION forming part of Design No. 25,735, dated June 30, 1896.

Application filed May 28, 1896. Serial No. 593,518. Term of patent 14 years.

To all whom it may concern:

Be it known that I, JOSIAH C. GOODING, a citizen of the United States, residing at St. Louis, in the State of Missouri, have invented 5 and produced a new and original Design for a Desk and Seat, of which the following is a specification, reference being had to the accompanying drawings, showing a part thereof.

Figure 1 represents a side view of a desk 10 and seat embodying my design, and Fig. 2 is a view in perspective thereof.

The leading feature of my design consists in the configuration of the supporting-frame-work for both the desk and seat, and comprising 15 in the first instance a strip of angle metal bent or shaped into an approximately straight inclined portion and an inwardly-curved portion, each portion being bent or curved outward at its lower end to constitute a foot, and 20 the two portions being intersected at their upper ends by an integral horizontal portion.

In the second instance the design comprises 25 a seat-support bent into reverse curves and spread or bifurcated at the upper end where it intersects the under side of the seat, and being joined to or intersecting at its lower end with the adjacent leg of the desk-frame.

Another leading feature of my design is a 30 side panel for the desk, which in height approximates about one-half the height of the desk-frame, and which is of corresponding contour and is flush at its edges with the edges of said frame, and which panel is embossed with a beading or molding and with a center-piece in representation of a twig or branch 35 with leaves and a single bud thereon.

In the drawings, A represents the desk as a whole, and B the seat. As viewed in side elevation at Fig. 1, the panel 1 constitutes an outer 40 side facing for the desk and is of height equal to the height of the body of the desk. The edges of the panel are flush with the edges of the main frame of the desk, and the obverse side of the panel is embossed with a continuous 45 beading or molding 2 following the general contour of the panel and lying a suitable dis-

tance within the edges or border-lines thereof and being joined or intersected by a cross beading or molding 3, subdividing the inclosure into an upper and lower part 4 and 5, respectively. The surface of the upper or smaller subdivision 4 is smooth or plain, while the center of the lower or larger subdivision 5 is embossed with a twig or branch 7, having leaves 8 thereon, and a single bud or blossom 9.

The main frame of the desk has the approximately straight and slightly-inclined leg 10, and the gradual inwardly-curved leg 11, each leg being bent outward to form a foot 12, and 60 the two being intersected or joined at the top by the integral horizontal portion 15. As before stated, the upright edges of the panel correspond to these forms.

By studying the perspective view, Fig. 2, 65 a better understanding will be had of the general design, and wherein it will be observed that the top 16 and front panel 17 of the desk are set within the edges of the frame and side panel, and they are each straight and smooth 70 or without ornamentation.

The seat B is of general rectangular shape, and is flat and smooth and is now referred to in connection with its supporting-frame 20. This latter comprises the member 21, bent for 75 its length into several reverse or compound curves 22, and intersecting or joining with the lower part of the leg 10 of the desk-frame. At its upper end the said frame is divided or spread apart at 25, so as to come directly beneath the seat at both the inner and outer 80 edges thereof at the corners 26 and 27.

What I claim, and desire to secure by Letters Patent of the United States, is—

The design for a desk and seat substantially 85 as herein shown and described.

In testimony whereof I affix my signature in presence of two witnesses.

JOSIAH C. GOODING.
